UNITED STATES PATENT OFFICE.

MORRIS J. HOFFMAN, OF CHICAGO, ILLINOIS.

COUPON-TICKET-PRINTING MACHINE.

Application filed November 14, 1921. Serial No. 514,901.

To all whom it may concern:

Be it known that I, MORRIS J. HOFFMAN, a citizen of the United States, and a resident of Chicago, Cook County, Illinois, have invented certain new and useful Improvements in Coupon-Ticket-Printing Machines, of which the following is declared to be a full, clear, and exact description.

This invention relates to coupon ticket printing machines, and its principal object is to provide a simple and comparatively inexpensive printing machine, wherein the type may be readily removed and replaced by other type and wherein any one type may be easily removed and replaced without disturbing any of the other type.

As is well understood, in many lines of industry a coupon ticket is employed for use in keeping an account of the employees' work upon an article or a "lot" of articles, and the coupons of the ticket must be prepared by writing or printing information upon them, and when it is understood that there may be from ten to fifty coupons on a ticket, it is quite evident that the task of writing the data upon the coupons is a long and tedious one, requiring great care and skill. The printing machine forming the subject matter of this specification has been designed to print information upon the coupons of coupon tickets wherein the data on each ticket may be the same or different from that of others of the coupon ticket, or it may in part be the same and in part may be different. The present machine has been designed to facilitate the work of preparing the coupon tickets and provides a simple and comparatively cheap machine which is easily manipulated and not likely to get out of repair. The invention consists in the several novel features of construction, arrangement and combination of parts hereinafter set forth and more particularly defined in the claims.

The invention is clearly illustrated in the drawing accompanying the specification, in which:—

Fig. 1 is a vertical cross-section through a coupon ticket printing machine embodying a simple form of the present invention; Fig. 2 is a central, vertical, longitudinal section taken on the line 2—2 of Fig. 1, with certain portions broken out to reduce the length of the view; Fig. 3 is a perspective view of a group of discs employed in the

construction of the type cylinder of the machine and one of the type used, the parts being detached from each other; Fig. 4 is a face view of two of the type used and Fig. 5 is a face view of a fragment of one form of coupon ticket used in connection with this machine.

Referring to said drawing, which illustrates a simple embodiment of the present invention, the reference characters 10, 10, 65 designate the two end frame members of the device, which, for convenience, may be in the form of rectangular panels, provided with feet 11, having rubber pads 12 secured therein. Said end frame members 10 may 70 be suitably spaced apart and connected together in any desirable manner to provide a rigid frame.

Journalled in bearing apertures in said frame members is a cylinder actuating shaft 75 13, which extends from one end of the machine to the other and supports the type cylinder 14, which contains the type that make the impressions on the coupon ticket. This type cylinder is of novel construction 80 and will now be described.

The type cylinder is made up of a multiplicity of thin discs, 20, 24, 25, and spacers 26, placed side by side and connected together by tie bolts or threaded rods 15, having heads 16 at one end engaging with one endmost disc and having nuts 17 threadedly secured on their threaded ends and bearing against the other endmost disc. By tightly screwing up the nuts 17, the discs are tightly 90 clamped together and to all intents and purposes form a cylindrical block or body. Each disc is centrally apertured to receive the shaft 13 and at said aperture is formed with a tongue 18 which enters a key way 19 95 formed in the shaft 13. This arrangement forms a positive connection between the shaft and cylinder, whereby the latter may be rotated by the shaft.

The discs are arranged in groups, there 100 being, as a preference, five discs to a group, as clearly indicated in Fig. 3, of which the centrally located disc 20 is greater in diameter than the other discs of the group. Said centrally located disc 20 is formed along its 105 periphery with equidistant notches or recesses 21, leaving therebetween tongues 22, between which the type 23 are received and held, as will be presently explained. On each side of the central disc 20 is a spacing 110

disc 24 of somewhat smaller diameter than the central disc 20 and on the outer sides of the spacing discs 24 are outer discs 25, whose diameter may be greater than that of the 5 spacing discs 24 and less than that of the central disc 20. Annular grooves are thereby left between the central and outer discs, as shown. Between each group of discs is a 10 spacer 26, comprising a disc or ring, which spaces the groups apart and said disc or ring 26 may be of the same thickness as the discs 20, 24, 25, or it may be greater, in order to space the groups apart sufficiently so that the type carried by each group may 15 occupy a correct position to print on the coupons of the ticket.

The type 23 are designed to be removably supported upon the type cylinder, and for this purpose, each type is formed with a 20 forked portion 27, which is arranged to straddle the marginal portion of each central disc 20 beyond the bottom of the notches 21. The forks of the forked portion 27 are made approximately as thick as the discs 25 24 and enter the grooves between the central disc 20 of the outer discs 25 of the group. The ends of the forks are arranged to bear against the peripheral edges of the discs 24, and the bottom 27^a of the notch between the forks 27 is arranged to bear 30 against the bottom of the notches 21 of the central disk 20. The type are also formed with lateral shoulders 28, which bear against the peripheral edges of the outer discs 25. It 35 will thus be observed that each type fits in and is confined in the notches of the central disc and bears against edge portions of all of the discs of a group. An extremely substantial backing is thus provided for the 40 type, and moreover, the forked portions are frictionally held between the central and outermost discs of each group. The type are formed with printing faces 29, 29^a, having type characters of any suitable description. 45

In Fig. 4 are shown two kinds of type characters. On one type are shown characters 29 designating prices or values, and on the other type is shown a type character 29^a designating "quantity", as for instance the number of articles in a "lot".

Surrounding the type cylinder 14 is a cylindrical type retaining casing 30 whose internal diameter is approximately the same 55 as the external diameter formed by the type cylinder and type contained therein. Said type retaining casing 30 is secured to the end frame members 10 by bolts or screws 31 and rigidly connects said end frame 60 members. In the upper side of the casing 30 is a slot 32 which extends parallel with the axis of the shaft, and extending away from said slot 32 along a horizontal plane approximately tangential with respect to 65 the face of the type, are flanges or webs 33

that act as a table or backing for the top-plate or cover 34 of the device. Between said flanges 33 and top-plate or cover 34 is placed an ink ribbon 35, the ends of which are secured to the flanges 33 or to some other stationary portion of the machine. Said ink ribbon extends across the slot 32 over the type. The top-plate or cover 34 is formed with a centrally located narrow slot 37, which is directly over the axis of the cylinder and exposes the ink ribbon over the type which are in printing position, that is to say, in a position directly over the axis of the cylinder. A guide or shoulder 38 is secured upon the top-plate or cover 34 beyond the slot 37 in position to enable the attendant to properly locate the coupon ticket when making an impression thereon.

Secured on one end of the shaft 13 is a handwheel or knob 50 by which the shaft 13, 85 and cylinder 14 may be rotated to bring any line of type into printing position. On said hand wheel or knob are characters 51, 52, designating or indicating the type characters on the cylinder, and on the adjacent 90 end frame member 10 is a finger 53 having the form of an arrow or pointer, which operates with the characters on the hand-wheel to indicate the printing position of the type cylinder.

For certain purposes, the cylindrical face of the type cylinder is divided into two semi-cylindrical portions, one portion of which is used for printing numbers which may designate "quantities" and the other 100 portion of the face of the cylinder may be used for printing prices or values or the amount of money paid for performing labor.

For instance, on one half of the cylinder, in one row of notches may be placed type 105 bearing the type character "1" and in the next adjacent row may be placed type bearing the type character "2" and so on, and on the corresponding side of the hand wheel are indicating characters, "1, 2, 3" etc., corresponding therewith. By turning the hand wheel until the character "1" thereon comes into register with the arrow 53, the line of type bearing the type character "1" is 110 brought into printing position.

In the other half of the cylindrical face may be set up type to indicate prices or values, as above stated, and each line may be set up to print the special prices for performing the several operations on the 120 goods. This is because the price paid for performing one operation on an article may differ from that paid for performing another operation thereon, consequently an arbitrary combination of prices may be set 125 up in each line. The characters "A, B, C," on the hand wheel indicate the peculiar combination of prices and by turning the hand wheel until the indicating character thereon corresponding with a given combi- 130

nation, registers with the arrow, said combination of type characters are brought into printing position.

A spring detent 54 secured to the end 5 frame co-operates with sockets or recesses 55 formed in a collar 56 mounted on the shaft 13 and releasably holds the cylinder in any printing position to which it is moved by the hand wheel.

10 Any suitable means may be provided for pressing the coupon ticket against the type or rather upon the interposed ink ribbon, to make impressions upon the tickets, and for the purpose of illustration I have shown 15 an impression bar 40 carried by arms 41 pivotally supported on ears or lugs 42 of the end frame members 10. Coiled compression springs 43 interposed between the end frame members and arms 41 act to throw 20 said arms upward and therewith raise the impression bar 40 away from the top-plate of the machine. Means are provided for bringing the impression bar down upon the ticket and said means may conveniently com- 25 prise a handle 44, which is mounted upon a rod 45 rotatably secured in the arms 41 and having secured thereon crank arms 46 that bear rollers 47 which engage with the undersides of brackets 48 that are secured 30 to and extend up from the end members and extend over the rollers 47. The impression bar is moved down by drawing the handle 44 forwards and down. When the handle 44 is moved forward and downward the rollers 47 35 are thereby caused to bear against the undersides of the brackets 48 and the rod 45 and arms are thereby moved downward. The impression bar 40 may comprise a tubular yielding member, as for instance a 40 piece of rubber tubing in which is contained a rigid backing bar, which is secured to the underside of the arms 41.

A coupon ticket, a fragment of which is seen at A in Fig. 5, is employed. As shown, 45 the ticket has a body portion a , and detachable coupons a' , which are to be printed upon. In the operation of the machine, the ticket is laid on the top plate with the edge of the coupons against the guide plate 38 and the handle 44 is depressed, thereby bringing the impression bar down on the coupons and forcing them against the ink ribbon over the line of type that is in printing position. The printing cylinder is 50 set to bring the desired line of type into printing position by turning the hand wheel 55 until the character thereon indicating the desired line of type, registers with the arrow 53.

60 When desired, any one type or any member of type may be removed from the cylinder and replaced by others, by bringing into printing position the line of type containing said type which is to be removed. The type 65 may then be withdrawn by the fingers or by a

pair of pliers and another type inserted in place.

While the type are frictionally held in place on the cylinder, I have found that by providing the cylindrical type retaining casting 30 around the cylinder, the type are positively prevented from falling out of the sockets in the cylinder. It is intended that the friction between the discs and type is only sufficient to hold the type in place when 75 external force is not applied to them in order that they may be readily removed when necessary.

More or less variation of the exact details of construction is possible without departing from the spirit of this invention; I desire, therefore, not to limit myself to the exact form of the construction shown and described, but intend, in the following 80 claims, to point out all of the invention disclosed herein.

I claim as new and desire to secure by Letters Patent:

1. In a printing machine, the combination of a supporting frame, a shaft journaled therein, a multiplicity of discs placed side by side on said shaft and secured thereon against rotation, and means for clamping said discs together to form a cylindrical body, certain of said discs being formed with 90 notches in their peripheral edges, and the notches in each disc being in line with the notches of the other discs, and type, having portions fitting in and confined in said notches and having shoulders bearing 95 against the edges of adjacent discs.

2. In a printing machine, the combination of a supporting frame, a shaft journaled therein, a multiplicity of discs placed side by side on said shaft and secured thereon against rotation, and means for clamping said discs together to form a cylindrical body, said discs being arranged in spaced groups, each group comprising a central disc notched along its peripheral 100 edge, a pair of spacing discs, of less diameter than the central disc, located one on each side thereof, and a pair of outer discs, located one on each side of said spacing discs, and there being annular grooves between said central disc and outer discs, and type having portions fitting in and confined in the notches of said central discs, and having forked portions straddling said central discs and entering said annular grooves, and 110 having also shoulders bearing against the edges of the outer discs.

3. In a printing machine, the combination of a supporting frame, a shaft formed with a keyway journaled therein, a multiplicity of centrally apertured discs placed side by side in said shaft, said discs having tongues entering said keyway of the shaft, tie bolts extending through said discs and securing them together to form a cylindrical 125

130

body, certain of said discs being formed with notches in their peripheral edges, and the notches in each disc being in line with the notches of the other discs, and type, 5 having portions fitting in and confined in said notches and having shoulders bearing against the edges of adjacent discs.

4. In a printing machine, the combination of a supporting frame, a shaft formed 10 with a keyway journaled therein, a multiplicity of centrally apertured discs placed side by side in said shaft, said discs having tongues entering said keyway of the shaft, tie bolts extending through said discs and 15 securing them together to form a cylindrical body, said discs being arranged in spaced groups, each group comprising a central disc notched along its peripheral edge, a pair of spacing discs, of less diameter than 20 the central disc, located one on each side thereof, and a pair of outer discs, located one on each side of said spacing discs, and there being annular grooves between said central disc and outer discs, and type having 25 portions fitting in and confined in the notches of said central discs, and having forked portions straddling said central discs and entering said annular grooves, and having also shoulders bearing against the edges 30 of the outer discs.

5. In a printing machine, a type cylinder formed with a multiplicity of circumferential grooves and comprising discs arranged in pairs with a web therebetween, said web 35 portions being formed with notches in its peripheral edge, substantially as and for the purpose set forth.

6. In a printing machine, a type cylinder, formed of a multiplicity of co-axial discs

placed side by side and secured together to 40 form a cylindrical body, said discs being arranged in groups each group comprising a central notched disc, outer discs and spacing discs intermediate the central and outer discs, said spacing discs being of less 45 diameter than the others, whereby annular grooves are left between said central and outer discs.

7. In a printing machine, the combination of end frame members, a type cylinder 50 rotatively supported thereby and formed with sockets in its peripheral face for the reception of type, type removably seated in said sockets, and held therein by friction, and a longitudinally slotted cylindrical type 55 retaining casing surrounding said type cylinder, the internal cylindrical face of said casing being placed adjacent the face of the type, substantially as and for the purpose set forth. 60

8. In a printing machine, the combination of end frame members, a cylindrical type retaining casing secured to and connecting said end frame members, said casing having a slot in its upper side, extending 65 parallel with its axis, and laterally extending horizontal flanges extending away from said slot, and a type cylinder rotatively mounted in said end frame members and concentrically with said casing, said cylinder being formed with type receiving sockets in its peripheral face, and type removably seated in said sockets and held therein by friction, with their type faces placed adjacent the internal cylindrical face of said 75 casing, substantially as and for the purpose set forth. 70

MORRIS J. HOFFMAN.
